WALL AND JOINT CONSTRUCTION

Peter Thomson, Wilmington, Del., assignor to
Modern Wall Construction, Inc., a corporation
of Delaware

Application May 22, 1933, Serial No. 672,296

7 Claims. (Cl. 72—44)

The present invention relates to building constructions and a primary object of the invention is to provide a building construction wherein precast building units are assembled and supported on a skeleton framing which carries the load of the building, and thereby requiring that the walls be no heavier than required to carry their own weight and to efficiently resist wind pressure against the walls which merely serve to enclose the structure.

A further object of the invention is to provide a building construction having double walls, with means for preventing passage of moisture to the inner wall.

15 A further object of the invention is to provide a double wall building construction having improved means for effectively sealing the joints between the outer wall units, and wherein the connecting members between the inner and outer walls are such as to prevent conveying of moisture between the walls.

20 A further object of the invention is to provide a building construction embodying means to compensate for any expansion and contraction of the structure and maintain perfectly sealed joints between the building units.

25 A still further object of the invention resides in the method and manner of constructing the outer wall unit for attachment to supporting columns in a manner permitting slight movement of the unit in any direction to compensate for expansion and contraction of the structure.

30 A further object of the invention is to provide a building construction wherein all piping, conduits, etc., may be installed in a concealed position within the walls and floors of the structure.

35 A still and important object of the invention is to provide a building construction permitting relatively large and high buildings being constructed from precast building units and at a cost considerably less than present forms of building constructions.

40 Other objects and advantages of the invention will be apparent from the following detailed description, taken in connection with the drawings forming a part of this specification and in which drawings:—

45 Figure 1 is a fragmentary vertical section thru a building constructed in accordance with this invention, the section being taken thru a window opening in the structure.

50 Figure 2 is an enlarged fragmentary vertical section above the window opening shown in Figure 1 and showing the manner in which ample space is provided for pipes, etc.

5 Figure 3 is a fragmentary horizontal section showing a construction at external and internal corners of the double wall and the manner in which a sealed joint is formed between units of the outer wall.

10 Figure 4 is an enlarged internal view taken substantially on the line 4—4 of Figure 1.

15 Figure 5 is a horizontal section on the line 5—5 of Figure 4 and showing the sealing joint between two outer wall units and the manner in which the inner and outer walls are spaced apart by non-absorbent elements.

20 Figure 6 is an enlarged fragmentary vertical section showing one of the horizontal joints between the outer wall units.

25 Figure 7 is an enlarged fragmentary section on the line 7—7 of Figure 5.

30 Figure 8 is an inside plan view of one of the building units for the outer wall.

35 Figure 9 is a fragmentary plan view of the outer flange of a supporting column for the outer wall unit.

40 Figure 10 is an enlarged fragmentary detail section at one of the eye bolts for an outer wall unit during casting of the unit.

45 Figure 11 is a view similar to Figure 10 but showing the eye bolt having been loosened prior to hardening or setting of the plastic material from which the unit is formed.

50 Figure 12 is a fragmentary perspective view of one of the sealing elements for the vertical joints.

55 In the drawings, and wherein similar reference characters designate corresponding parts thruout the several views, the letter A designates a steel supporting framing upon which are assembled the various building units to provide a double exterior wall embodying an outer section including outer wall units or slabs B and an inner section including inner wall units or slabs C. The letter D may designate the floor structures as a whole, while the letter E may designate the roof structure.

40 The steel framing A for carrying the load of the building embodies the columns or uprights 5 which are in the form of I beams which extend from the foundation to the roof of the structure in spaced relation along the straight wall portions. At the external corners of the building as shown in Figure 3, built up columns or uprights 6 are preferably employed, while at the internal corners, built up columns or uprights 7 are preferably employed. The columns 6 and 7 may be of other shapes than that shown so long as the columns present suitable portions 55

for attachment of the inner and outer wall units in spaced relation. The columns 5 are connected along their inner flanges 8 and at each floor level with horizontal tie members 9 preferably of angle formation and having their ends secured as by riveting, bolting or the like as at 10 in Figure 4 to the columns 5. Two of these tie members are provided at each floor level and form supports for the floor structures D and the 10 roof structure E.

Referring now to the outer wall section of the exterior wall, the same is formed of the outer wall units B which are in the form of molded and reinforced slabs preferably molded from a plastic material such as concrete. Referring particularly to Figure 8 showing one of the molded units or slabs formed with a window opening, the metallic casement window frame 11 is embedded in the unit during molding. In the case of doors or other openings, the framing for the opening is placed in the unit during molding. Embedded in each outer wall unit or slab B are vertically disposed reinforcing rods or bars 12 which terminate short of the upper and lower edges of the units and these vertical reinforcing bars extend thru eyes 13 formed at the ends of horizontal reinforcing rods or bars 14 which form ties between the vertical rods. Arranged in vertically spaced relation along each vertical edge of the outer wall unit is a series of coupling members 15 preferably in the form of eye bolts which are embedded in the molded material and have the vertical reinforcing bars 12 extended thru the eyes 16 of the bolts as clearly shown in Figures 5 and 7 and with the threaded shank portions 17 of the bolts projecting beyond the inner surface of the molded material.

Referring particularly to Figures 10 and 11, Figure 10 shows the outer wall unit having been 40 molded with the coupling members or eye bolts in place, and before the material has set or hardened the eye bolts are moved about by grasping the projecting end portions 17 and the eye bolts loosened as illustrated in Figure 11 to 45 provide an enlarged pocket 18 for the eye bolts whereby they are permitted to move fractionally in any direction so as to compensate for expansion and contraction of the building structure. This manner of loosening the eye bolts 50 also eliminates exact alignment of the eye bolts being required when connecting the wall units to the metal framing.

In the case of an external corner construction as at the upper portion of Figure 3, the outer 55 wall unit B' is formed with an angularly offset end and the horizontal reinforcing rods 14' are also offset so that the eye at one end thereof may receive a vertically disposed reinforcing rod. This construction aside from disposing the eye 60 bolts in proper position for connection to the framing upright 6, also disposes the joint between vertical edges of the building units in proper relation to the supporting columns to provide a seal joint as will be subsequently described.

Each vertical end edge of the outer wall unit is beveled as at 20 with the beveled surfaces terminating inwardly of the outer or face surface of the unit. These beveled surfaces 20 upon assembling of the outer wall units provide V-shaped pockets along the vertical edges of adjacent units having confronting relation to flat surfaces of the supporting columns to which the units are attached. As shown more clearly in 70 Figure 6, the upper horizontal joint forming

edges 21 of the units B are formed with a reverse or S-shaped curve having the convex portion of the curve adjacent the inner or rear face of the units, while the lower edge 22 of each unit is formed with a reverse or S-shaped curve having the convex portion of the curve adjacent the outer face of the unit whereby the convex portions of adjacent units confront concaved portions of the edges.

Referring now to the arrangement of the steel framing A for supporting the building units, the supporting columns or uprights 5, 6 and 7 are spaced apart proper distances so that the vertical edges of the units B will overlap adjacent columns to which the units are connected along their vertical edges. The columns 5 for use along straight wall portions are in the form of I beams and have their outer flanges 23 provided with vertical rows of apertures 24 as clearly shown in Figure 9 for receiving the shanks of the eye bolts 15 whereby the wall units are secured to the columns by nuts 25 threaded upon the threaded shank portions 17. As shown in Figure 5, the vertical edges of the units B are slightly spaced apart at their outer surfaces beyond the V-shaped pockets formed by the bevels 25. Referring particularly to Figure 3, the built up column 6 for use at external corners consists of two T beams 26 and 27 having one flange of the beam 27 secured to the web or stem of the beam 26. The flanges of the beam 26 are apertured to receive the shanks of the eye bolts for securing the outer wall units to the column. The built up column 7 for use at internal corners 30 preferably consists of a T beam 28 having its stem or web secured to one flange of a channel beam 29.

The vertical joints between the exterior wall units B are sealed by resilient sealing members 30 extended along the outer surfaces of the supporting columns. These sealing members or strips 30 are formed of cork or some such similar material and embody triangular-shaped wedge portions 31 from each side of the base of which extend flanges 32. The sealing members 30 have their flanges 32 apertured as at 33 to align with the apertures 24 in the supporting columns and receive the eye bolts 15. The sealing members 30 are disposed with their flat sides engaging the flat outer flanges of the supporting columns and the wedge portion 31 engaging in the V pockets formed between the vertical edges of adjacent wall units. When the wall units B are assembled upon the framing A, and the nuts 25 tightened, the sealing members 30 are compressed sufficient 55 to make a tight joint and yet provide enough resiliency to permit expansion and contraction of the parts joined and still resist entrance of moisture to the inner surface of the exterior wall. The vertical joints outwardly of the resilient sealing members 30 are closed by a suitable plastic material such as at 34 to provide a better appearing joint and act as protection to the sealing member. The pockets 18 for the eye bolts, formed by loosening the eye bolts during molding of the wall units, will permit fractional movement of the exterior wall units in any direction to compensate for expansion and contraction of the structure.

The horizontal joints between the exterior wall units are sealed by a resilient sealing strip 35 as shown more clearly in Figure 6, and this sealing strip is of a width less than the thickness of the wall unit to permit placing of a plastic finishing 75

36 along the joints at the outer surface of the wall.

Thus it will be seen that the vertical and horizontal joints between the outer wall units B are sealed by resilient sealing members or strips providing perfectly sealed joints permitting slight movement due to expansion and contraction, and that the units are so secured to the supporting framing as to also compensate for expansion and contraction.

10 The floor structures D preferably consist of bar joists 37 of conventional construction having their upper and lower rails supported upon and secured thereto as by welding, riveting or the like 15 to the horizontal tie members 9. The upper side of the bar joist 37 supports a suitable flooring 38, and a ceiling 39 is secured in any preferred manner to the under side of the bar joists.

15 The roof structure E embodies bar joists 37 supported at their ends upon the horizontal tie members 9 and supporting a roof 40 of any approved construction and provided about its margins with an upstanding flange 41.

20 The inner section of the double exterior wall construction is built up of the inner wall units or slabs C which may be formed of a plaster composition or other suitably formed slabs such as are now in general use for interior wall constructions. The inner units C are provided along their 25 vertical edges with openings 42 for receiving countersink screws 43 which, in the case of the columns 5 are threaded into tapped openings 44 provided in the inner flanges 8 of the columns. Where partitions are desired as shown in Figure 30 5, the partition slabs 45 have a vertical edge interfitting in a pocket formed by spacing the ends 35 of the inner wall slabs C.

25 Referring particularly to Figure 3, the T column 27 provides an internal corner for the wall units C and the stem and one flange of the column are tapped as at 46 to receive the fastening screws 43. The channel 29 of the column 7 has one flange and its web portion tapped as at 47 for receiving the fastening screws 43. Thus the portions 27 and 29 of the built up columns 6 and 7 respectively, provide means for securing the inner wall units in parallel spaced apart relation to the outer wall units. From Figures 1, 2 and 4 it will be noted that the inner wall units C merely extend from the floor 38 to the ceiling 39 and do not traverse the space between the horizontal tie members supporting the bar joists 37.

30 The supporting columns 5, 6 and 7 provide an open space between the outer and inner wall units B and C respectively, which extend from the base to the top of the double wall structure and this space has communication between the horizontal tie members 9 with the horizontal open spaces formed between the floor 38 and ceiling 39 by the 35 open bar joists 37. The vertical open spaces formed between adjacent columns of the supporting frame provide spaces for installation of pipes, wires and such within the exterior walls and access may be had to these vertical spaces by means of removable slabs or panels such as indicated at C' in Figure 4. Concealed between the outer and inner wall units B and C respectively is a vertically disposed drain pipe 50 to which is connected branch drain pipes 51 which extend 40 between the horizontal tie members 9 supporting the floor structures for connection to various fixtures. The upper end of the drain pipe 50 extends thru the roof 40 and may be provided with a suitable strainer 52 for carrying off roof water.

45 75 This arrangement for taking care of the roof

water eliminates the usual extending of gutters about the margins of the roof and allows for the drain pipe to be concealed within the double wall.

50 Connecting the outer and inner wall units B and C respectively at the window frame 11 is a metal casing 55 which aside from closing the vertical space between the wall units, also serves as a reinforcement for the middle portions of the inner and outer wall units. The outer end of the metal casing 55 is secured in any preferred manner to the frame 11, while the inner portion of the casing is secured by suitable fastening elements 56 to vertically disposed angle uprights 58 which may be secured to the horizontal tie members 9. These angle uprights 58 have one flange 15 provided with suitably spaced tapped openings for receiving the fastening screws 43 whereby the inner wall units may be secured in position along the vertical edges of the metal casing 55.

20 Thus it will be seen that the outer and inner sections of the double wall are separated by the metallic members 5, 6, 7 and 55 and that there are no connections between the wall sections which would tend to convey moisture from the outer wall section to the inner wall section. With 25 the joint between the outer wall units B perfectly sealed by the sealing members 30 and 35, any moisture entering the space between the outer and the inner wall units would need to soak thru the material of which the outer wall is composed, 30 and since the outer wall section is separated from the inner wall section by the steel columns 5, 6 and 7 and the metal casing 55, before any moisture can reach the inner wall the moisture would need to travel by way of the metal separating elements between the outer and inner walls with the result that little or no moisture would ever reach 35 the inner wall because of the non-absorbent quality of the metal.

40 It will be noted that the steel framing carries the entire load of the building walls which are secured to the framing in such manner as to provide a double wall with the sections thereof spaced apart by framing elements serving to prevent 45 passage of moisture from one section of the wall to the other. The open air spaces between the walls also allow for a circulation of air which will dissipate moisture absorbed by the outer wall. A novel means for providing a perfect seal between joints of the outer wall units is also provided, as well as means for securing the outer 50 wall units to the supporting framing in a manner to compensate for expansion and contraction of the structure without causing an opening to be formed at the joints.

55 Changes in details may be made to the form of invention herein shown and described, without departing from the spirit of the invention or the scope of the following claims.

I claim:

1. A building comprising a metal framing including vertical wall columns and horizontal bar joists supported in vertically spaced relation by the columns, outer wall units secured to the outer sides of the columns, inner wall units secured to 65 the inner sides of the columns above and below the bar joists, said outer and inner wall units providing vertical air spaces thruout the height of the walls, a floor supported on the upper side of the bar joists, and a ceiling secured to the under side of the bar joists, said floor and ceiling providing horizontal air spaces having communication with the vertical air spaces at each wall of the building.

2. A building comprising an exterior wall in-

- cluding parallel spaced apart metallic uprights provided along their outer sides with vertical rows of plane openings and along their inner sides with vertical rows of tapped openings, a series of 5 molded outer wall units having their vertical edges overlapping the outer side of adjacent uprights, a resilient sealing member between the vertical edges of the units, fastening elements embedded in the units along their vertical edges and having threaded shank portions for extending thru said plane openings, nuts threaded upon the threaded shank portions for securing the units to the uprights, sealing means between the horizontal edges of superposed units, a series of 10 inner wall units having their vertical edges overlapping the inner sides of adjacent uprights, and threaded fastening elements along the vertical edges of the inner wall units for threading into 15 said tapped openings.
- 20 3. A wall including in combination, parallel spaced apart I columns having apertured outer flanges, molded wall units having beveled vertical edges overlapping the outer flanges of adjacent columns, a resilient sealing member for each column including a triangular rib portion engaging the beveled edges of the units and flanges engaging the column flanges and having apertures aligning with the apertures in the column flanges, a series of bolts anchored in the units 25 along each vertical edge portion thereof with the shanks of the bolts extending thru the aligning apertures in the sealing members and column flanges, and a nut threaded on each of said shanks for securing the units to the columns.
- 30 35 4. A wall including in combination, parallel spaced apart uprights having flat outer faces, outer wall units having beveled vertical edges overlapping the outer faces of adjacent uprights,
- a resilient sealing member disposed between the outer face of the uprights and overlapping edges of the wall units and having triangular-shaped rib portions engaged with a wedging fit by the beveled edges of the wall units, and means for separately fastening the wall units to the uprights.
- 5 5. A wall comprising in combination, parallel spaced apart uprights, outer wall units having their vertical edges overlapping adjacent uprights, a resilient sealing member between the vertical edges of the units and spaced inwardly from the outer face of the units, means for securing the units along their vertical edges to the uprights, a resilient sealing member between the horizontal edges of superposed wall units and spaced inwardly from the outer face of the units, and a plastic filler filling the vertical and horizontal joints between the wall units outwardly of the sealing members.
- 10 15 6. A wall comprising in combination, supporting uprights, moulded wall units secured at their vertical edges to the uprights and having interfitting S curved upper and lower edges, and a resilient sealing strip substantially filling the joint of said interfitting edges and having its outer edge spaced inwardly of the outer face of the units.
- 20 25 30 35 7. A building unit comprising a moulded slab having beveled vertical edges with the bevels terminating inwardly of the outer face of the slab, and S curved upper and lower edges, the upper edge having its convex portion adjacent the inner face of the slab and the lower edge having its convex portion adjacent the outer face of the slab, and securing elements carried by the slab and projecting from the inner face thereof.

PETER THOMSON.
